Primary Examiner — Susan Bennett Hattan*Assistant Examiner* — Brett Miller(74) *Attorney, Agent, or Firm* — R. Reams Goodloe, Jr.(57) **CLAIM**

The ornamental design for a lid for beverage container, as shown and described.

DESCRIPTION

FIG. 1 is a perspective view of a lid for beverage container showing the novel design.

FIG. 2 is a front side view, therefore.

FIG. 3 is a back side view, therefore.

FIG. 4 is a left side view, therefore.

FIG. 5 is a right side view, therefore.

FIG. 6 is a top plan view therefore; and,

FIG. 7 is a bottom plan view therefore.

The broken lines in the drawings depict environmental subject matter only and form no part of the claimed design.
